Primary Examiner — Derrick E Holland*Assistant Examiner* — Jennifer O King(74) *Attorney, Agent, or Firm* — McCormick, Paulding & Huber LLP(57) **CLAIM**

The ornamental design for a car charger and mount for hand-held electronic devices, substantially as shown and described.

DESCRIPTION

FIG. 1 is a front, bottom perspective view of a car charger and mount for hand-held electronic devices comprising a new, original and ornamental design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown represent portions of the car charger and mount for hand-held electronic devices that form no part of the claimed design.

1 Claim, 10 Drawing Sheets(56)
